W. F. SNOHR

STREET CAR BARN

Filed Feb. 10, 1922

Inventor.

William F. Snoker,

Byzenforth, Sir, Chittenden, Miles,
1775

UNITED STATES PATENT OFFICE.

WILLIAM F. SNOHR, OF CHICAGO, ILLINOIS.

STREET-CAR BARN.

Application filed February 10, 1922. Serial No. 535,622.

To all whom it may concern:

Be it known that I, WILLIAM F. SNOHR, a citizen of the United States, residing at Chicago, in the county of Cook and State 5 of Illinois, have invented a new and useful Improvement in Street-Car Barns, of which the following is a specification.

This invention relates to street car barns and the like.

10 The primary object of the invention is to provide means whereby street cars can be quickly moved in case of a fire in the car barn.

Another object is to provide means for 15 signalling when said means is operated and for simultaneously closing fire doors, curtains and partitions, so as to localize any fire that may start in the car barn.

These and other objects are accomplished 20 by this invention, which is fully described in the following specification and shown in the accompanying drawing, in which the figure is a diagrammatic plan view of a car barn equipped with my invention.

25 The embodiment illustrated comprises a car barn having side-walls 10 having openings 11 therein, through which are laid car-tracks 12 in any well known manner. Overhead trolley wires 13 are supported 30 above the tracks and these are connected to the two main trolley wires 14 and 15 and consequently are always charged.

A second trolley wire 16 is placed along 35 side each trolley wire 13 and insulated therefrom by a suitable insulator 17, at each end thereof. These are connected by means of a lead 18, a switch 19 and a lead 20 with the trolley wire 14. Normally the switch 19 is open as shown, so that these trolley wires 40 16 are "dead."

The operation of this much of the system is as follows: Cars (not shown) are run into the car barn, the car controllers are turned to neutral position and the trolleys are removed from the charged or "live" trolley wires 13 and placed upon the dead trolley wires 16. In case of fire, the switch 19, which is preferably located in the superintendent's office, is closed and all the trolley wires 16 50 become charged. The trolleys are already on these wires and a great deal of time is thereby saved over the present method of using a single trolley and having to replace each trolley upon the wire before the car can

be started, as is now commonly done. The 55 time required to empty a car barn of cars is consequently greatly reduced, and in case of fire, the number of cars it would be possible to save in a given time would be greatly increased.

While only one switch 19 is shown, it will be understood that a separate switch may be used on each trolley wire 16, if desired.

A lead 21 connects the city fire alarm system (not shown) with the lead 18, through 65 the switch 22 which is normally closed. When, therefore, the switch 19 is closed, the city fire alarm is sounded.

In the same way the lines 21^a and 21^b operate respectively a local fire alarm and 70 mechanism for closing fire doors, curtains and partitions for dividing the car barn into sections, so as to prevent the rapid spread of the fire.

While I have shown and described certain 75 embodiments of my invention, it is to be understood that it is capable of many modifications. Changes, therefore, in the construction and arrangement may be made without departing from the spirit and scope 80 of the invention as disclosed in the appended claims, in which it is my intention to claim all novelty inherent in my invention as broadly as possible in view of the prior art.

What I claim as new and desire to secure 85 by Letters Patent, is:

1. In a street car barn and the like, a track, a live trolley wire adjacent the track, a dead trolley wire insulated from said live trolley wire and parallel thereto, so that 90 a trolley of a car on said track may readily be shifted to either trolley wire, and means for connecting said dead trolley wire with a source of electric current.

2. In a street car barn and the like, a plurality of tracks, a live trolley wire adjacent each track, a dead trolley wire insulated from each live trolley wire and parallel thereto, so that a trolley of a car on one 100 of said tracks may readily shifted to either trolley wire, and means for connecting said dead trolley wires with a source of electric current.

3. In a street car barn and the like, a plurality of tracks, a live trolley wire adjacent each track, a dead trolley wire insulated from each live trolley wire and parallel thereto, so that a trolley of a car on one of 105

said tracks may be readily shifted to either trolley wire, and a switch for connecting said dead trolley wires with a source of electric current.

5. 4. In a street car barn and the like, a plurality of tracks, a live trolley wire adjacent each track, a dead trolley wire in-

sulated from each live trolley wire and parallel thereto, so that a trolley of a car on one of said tracks may be readily shifted to either trolley wire, and means for connecting said dead trolley wires in parallel with a source of electric current.

WILLIAM F. SNOHR.
